(57) **CLAIM**

The ornamental design for a watch face, substantially as shown and described.

DESCRIPTION

FIG. 1 is a top plan view of the watch face showing the ornamental design which is in the form of a guitar pick. The watch dial, case, numerals and hands and are in broken lines to show the environment of the invention, but form no part of it.

FIG. 2 is a bottom plan view in broken lines of a watch case in which the ornamental design is placed. The watch case is in broken lines to show the environment of the invention, but form no part of it.

FIG. 3 is a side view in broken lines of a watch case in which the ornamental design is placed. The watch case is in broken lines to show the environment of the invention, but form no part of it.

FIG. 4 is a view similar to FIG. 3 but showing the opposite side of the watch case.

FIG. 5 is a front view in broken lines of a watch case in which the ornamental design is placed. The watch case is in broken lines to show the environment of the invention, but form no part of it; and,

FIG. 6 is a view similar to FIG. 5 but showing the opposite side of the watch case.
